BUNCH BUILDING MECHANISM FOR SPINNING OR WINDING MACHINES

William H. Buckner, Starkville, Miss., assignor to Talladega Foundry and Machine Company, Talladega, Ala., a partnership

Application January 26, 1949, Serial No. 72,808

2 Claims. (Cl. 242—43.7)

1

This invention relates to a novel mechanism for use with conventional spinning or winding machines for causing a preliminary winding or bunch to be applied to a bobbin or quill to insure that the machine will thereafter lay a full pick of filling.

More particularly, it is an aim of the present invention to provide a novel buncher guide which may be demountably attached to and supported by the builder arm of a spinning or winding machine for cooperation with the buncher disk to cause the machine to execute a short stroke for laying the bunch on the bobbins or quills and which will thereafter release the buncher disk to render it inoperative and so that the machine can thereafter function in a conventional manner for laying a full supply of yarn on the bobbin.

More particularly, it is an aim of the present invention to provide such a construction of buncher guide, constituting the present invention, which is actuated by engagement with the conventional buncher disk of the machine and which includes a threaded member engaged by the buncher disk and caused by frictional engagement therewith to revolve with the buncher disk until said disk rides out of engagement with the buncher guide and at which time the bunch will have been applied to the bobbins.

A further object of the invention is to provide such an attachment having an adjustable weighted means for causing the attachment to resume its initial position when the machine is reset for laying a bunch on another set of bobbins and to insure the laying of a bunch of uniform size on successive sets of bobbins.

Still a further object of the invention is to provide a buncher guide attachment for spinning and winding machines of extremely simple construction which is capable of being economically manufactured and sold and which may be very quickly and easily applied to spinning machines already in existence to afford a means whereby such machines will function to accurately apply bunches of various sizes to bobbins or quills and which after being set will apply bunches of uniform sizes to successive sets of bobbins until resetting of the buncher guide.

Numerous other objects and advantages of the invention will hereinafter become more fully apparent from the following description of the drawings, illustrating a presently preferred embodiment thereof, and wherein:

Figure 1 is a fragmentary perspective view showing a portion of a conventional spinning machine with the attachment applied thereto;

Figure 2 is a vertical sectional view taken substantially along a plane as indicated by the line 2—2 of Figure 1 and showing the buncher guide attachment in an operative position;

Figure 3 is a view similar to Figure 2 and showing the buncher guide attachment after it has assumed an inoperative position;

2

Figure 4 is a substantially central longitudinal sectional view partly in side elevation of the buncher guide attachment;

Figure 5 is a cross sectional view thereof taken substantially along a plane as indicated by the line 5—5 of Figure 4;

Figure 6 is a view similar to Figure 5 but showing the adjustable element of the attachment in a different position from that illustrated in Figure 5;

Figure 7 is an elevational view of a bobbin or quill showing the original build of yarn on the bobbin produced by the normal operation of the machine and after the buncher guide attachment has completed its operation, and

Figure 8 is a view similar to Figure 7 showing the bunch applied to the bobbin or quill by the operation of the buncher guide in combination with the buncher disk of the spinning machine.

Referring more specifically to the drawings, for the purpose of illustrating the application and operation of the buncher guide attachment, comprising the invention and which is designated generally 10, a portion of a conventional spinning machine has been illustrated in Figure 1 and is designed generally 11 and includes such parts as function in combination with the attachment 10 or as are affected by the operation of said attachment. One side wall 12 of the spinning machine 11 is shown and it will be understood that said machine likewise includes a corresponding opposite side wall, not shown, which side walls provide a support for the upper and lower rails 13 and 14. The upper rail 13 provides the conventional bobbin or quill support on which a plurality of bobbins 15 are rotatably supported in upright positions for receiving the strands of yarn 16 from a suitable supply source 17 and which are adapted to be wound thereon in a conventional manner. The bobbins 15 are revolved in a conventional manner by a driven belt means 18. The bobbins or quills 15 extend upwardly through openings in a conventional ring rail 19 which is supported by a plurality of push rods which extend reciprocally through the members 13 and 14, but one of which is shown at 20 in Figure 1. Each of the push rods 20 is provided at its lower end with a foot member 21 which engages on a roller 22 which projects laterally from the free end of a lever 23 which is fixed to a shaft 24 which shaft is suitably journaled in bearings, not shown, of the machine 11 and has an upwardly extending arm 25 which is fixed thereto and has a segment portion 26 at its upper end to which is connected one end of a flexible member 27. A weight 28 is likewise fixed to and projects from the shaft 24 in a direction opposite to the lever 23 for urging said shaft 24 to rock in a direction for swinging the lever 23 upwardly to exert an upward thrust on the push rod 20 for elevating the rails 19. The flex-

ible member 27 extends substantially horizontally from the segment 26 and has its intermediate portion trained over a pulley 29 which projects inwardly from the wall 12 and extends downwardly from said pulley and is fastened at its opposite end to the builder arm 30 which is journaled at a point remote to the flexible member 27 on a shaft 31. The parts of the builder arm 30 which have been illustrated in Figure 1 and which function in a conventional manner will not be described except for the roller 31 which is supported on a bracket 32, as illustrated in Figures 1, 2 and 3. A driven shaft 33, having a portion journaled in the wall 12, extends transversely across the builder arm 30 and has a main builder cam 34 fixed thereto and disposed over the roller 31 for engagement therewith when the builder arm 30 is in its position of Figure 3 and so that as the roller 31 rides over the high and low portions of the periphery of the cam 34 said builder arm 30 will be rocked vertically for exerting a pull on the flexible member 27 as the builder arm 30 swings downwardly to rock the lever 23, shaft 24, arm 25 and weight 28 in a counterclockwise direction as seen in Figure 1 to permit the rail 19 and its supporting rods 20 to move downwardly relatively to the bobbins 15; whereas, when the roller 31 moves into engagement with a low point cam 34 the arm 30 is swung upwardly by the weight 28 which causes the shaft 24, arm 25 and lever 23 to swing clockwise and so that the roller 22 will exert a thrust on the push rod 20 for displacing the rail 19 upwardly relatively to the bobbins 15. The driven shaft 33 also has a buncher disk 35 adjustably fixed thereto by means of a setscrew 36 which extends radially through the hub of the disk 35 and which disk is disposed over the buncher guide attachment 10. The buncher disk 35 is provided with scalloped periphery 37 for a purpose which will hereinafter become apparent. The parts 11 to 37, previously described and illustrated in Figure 1 form no part of the present invention but have merely been illustrated and described briefly to afford a better understanding of the buncher guide attachment 10 which comprises the invention and which functions in combination with the buncher disk 35 to initially cause the machine 11 to apply a bunch of a predetermined size to a selected part of the bobbins or quills 15.

Said buncher guide attachment 10, as best illustrated in Figures 2 to 6, includes a supporting bracket 38 which is generally U-shaped and has a shorter upstanding leg 39 which is fastened to the builder arm 30 by fastenings 40 on the side thereof opposite the side from which the bracket 32 extends and which fastenings 40 demountably support the builder guide 10 on the spinning machine 11. The other, longer upstanding leg 41 of the bracket 38 has a longitudinally or vertically elongated opening 42 formed therein for receiving the restricted threaded shank 43 which projects from one end of a shaft 44 through a portion of the opening 42 and to which a nut 45 is applied to combine with the annular shoulder formed around the end of the shaft 44 from which the threaded stem 43 projects for adjustably clamping said shaft 44 on the bracket 38 so that said shaft may be mounted at various levels relatively to the builder arm 30, for a purpose which will hereinafter become apparent.

An elongated guide member 46 is rotatably supported on the shaft 44 adjacent the bracket 38 and the end thereof located nearest the

bracket 38 is provided with a relatively deep thread 47. The opposite, unthreaded end 48 of the guide member 46 is provided with an internal recess 49 for containing a segment-shaped weight 50 having an outwardly opening threaded recess 51 intermediate of its ends for receiving the threaded shank of a setscrew 52 which extends through a portion of a circumferentially elongated opening 53 formed in the cylindrical portion 48. The setscrew 52 is tightened for clamping the weight to the member 46 and it will be readily apparent that said setscrew can be loosened and adjusted circumferentially of the member 46 for adjustably positioning the weight 50 circumferentially of the guide member 46, for a purpose which will hereinafter become apparent.

A spring stop 54 is adjustably positioned on the shaft 44 adjacent its opposite end and remote to the bracket 38 by a setscrew 55 and said spring stop 54 is provided with openings 56 in an annular flange portion thereof which are sized to reciprocally receive the threaded ends of a pair of rods 57 having corresponding ends extending from the stop 54 toward the guide member 46 and terminating in restricted threaded terminals 58, as seen in Figure 4, which engage in threaded recesses 59 of a disk 60 which is slidably mounted on the shaft 44 and which bears against the annular free end of the guide portion 48. Each rod 57 carries an expansion coiled spring 61 bearing at its ends against adjacent sides of the spring stop 54 and disk 60 for yieldably urging said disk 60 toward the bracket 38 to normally retain the guide member 46 against the outer leg 41 of the bracket 38. The threaded opposite, first mentioned ends of the rods 57 are preferably each provided with a nut 62 which nuts engage the outer side of the spring stop 54 and are adjustable for varying the extent that the springs 61 can move the disk 60 toward the bracket 38.

To apply a bunch 63, as illustrated in Figure 8, to a plurality of bobbins or quills 15 which are mounted in the spinning machine 11, the buncher disk 35 is initially set by means of the setscrew 36 in a desired position on the driven shaft 33 and the buncher guide 10 is vertically adjusted to a desired position in the slot 42, as previously described. The builder arm 30 can then be manually swung downwardly to position the guide member 46 beneath the lowermost point of the buncher disk 35 and the spring 61 will then move the buncher guide 46 to the left and into its position of Figures 2 and 4 against the bracket portion 41. The arm 30 is then released and swung upwardly by the weight 28 so that a portion of the fluted edge 37 of the disk 35 will engage in the spiral groove of the thread 47, as illustrated in Figure 4, for holding the arm 30 sufficiently depressed so that the roller 31 will not contact any part of the cam 34. As the disk 35 is driven by the shaft 33 its scalloped edge 37 by engagement with the groove of the thread 47 will revolve the member 46 therewith and so that said parts will be turned in directions to cause the fluted edge 37 to move toward the left-hand end of the member 46 due to the fact that said member 46 will be displaced from left to right of Figures 2, 3, and 4 as it is revolved by the engagement of the buncher disk 35 with its thread 47 and against the action of the springs 61 which will be compressed to permit the member 46 and the spring follower disk 60 to move from left to right on the shaft 44 so that the guide member

46 not only revolves but reciprocates relatively to the shaft 44 during this rotary movement of the buncher 35 and buncher guide member 46. The valleys between the points of the scolloped edge 37 will produce a slight vertical rocking movement of the builder arm 30 which will be transmitted as previously described to the rail 19 to cause the bunch 63 to be applied over a relatively restricted area lengthwise of the bobbins or quills 15. When the scolloped edge 37 moves out of engagement with the left-hand end of the thread 41 it will assume the position of Figure 3 and so that the weight 28 can swing the builder arm 30 upwardly to displace the roller 31 upwardly and into engagement with the cam 34 which will thereafter function to rock the roller arm 30 vertically through a greater arc, as previously described, for laying the regular service winds. It will be readily apparent that after the bobbins or quills have been filled and removed and replaced by another set of bobbins or quills, that the aforescribed operation can be repeated for laying the yarn on the new set of bobbins or quills and that by again moving the builder arm 30 downwardly the spring 61 will return the bunch guide member 46 to its initial position as illustrated in Figure 4 to function with the buncher disk 35 to apply the bunch initially to the new sets of bobbins. It will also be readily apparent that by vertically adjusting the buncher member 46 relatively to the bracket 38 by means of the slot 42, that the location of the bunch on the bobbins or quills can be varied longitudinally of the bobbins.

To insure the application of bunches of uniform sizes to successive sets of bobbins or quills the adjustable weight 50 is provided and it will be readily obvious that by circumferentially adjusting the weight 50 by means of the setscrew 52 and slot 53, that the location of the center of said weight with respect to the left-hand end of the spiral thread groove 41 off of which the scolloped edge 37 moves, can be varied. Since this together with the location of the buncher disk 35 on the shaft 33 determined the size of the bunch 63, to produce bunches of uniform size on successive groups of bobbins makes it necessary that a corresponding portion of the groove of the thread 41 be positioned each time to initially receive the scolloped edge 37 to commence the forming of the bunches and which is accomplished by the weight 50 since when the edge 37 is out of engagement with the thread 41, said weight will cause the guide member 46 to turn sufficiently to permit the weight to assume a lowermost position as illustrated in Figures 5 and 6. Assuming that the left-hand end of the thread 41, representing the point on the guide 46 where the scolloped edge 37 moves out of engagement with the bunch guide member 46, is located in longitudinal alignment with the left-hand end of the slot 53, as seen in Figures 5 and 6, it will be readily apparent that by displacing the weight 50 in a clockwise direction as seen in Figures 5 and 6, will result in the disk 35 traveling a further distance in the thread groove with a predetermined setting on the shaft 33 and accordingly applying a greater amount of yarn to the bunch.

Various modifications and changes are contemplated and may obviously be resorted to, without departing from the spirit or scope of the invention as hereinafter defined by the appended claims.

I claim as my invention:

1. A bunch builder attachment for use with winding and spinning machines comprising a buncher disk adapted to be adjustably secured to a driven cam shaft of a spinning or winding machine for rotation therewith, a buncher guide operating with said buncher disk for applying bunches to spindles or quills of the machine including a supporting bracket adapted to be demountably fastened to a swingably mounted builder arm of the machine, a buncher guide shaft secured to said bracket and projecting therefrom in substantially a horizontal plane, a buncher guide member rotatably and slidably mounted on said buncher guide shaft having a threaded peripheral portion receiving the periphery of the buncher disk, and spring means supported by the buncher guide shaft and spring biasing the buncher guide member toward the bracket, said buncher guide member being rotated by engagement with the rotating buncher disk and having the thread thereof pitched to cause the buncher guide member to be displaced away from the bracket to release the buncher disk from an end of the threaded portion thereof for movement into the space between the bracket and buncher guide member, said buncher guide member when in engagement with the buncher disk functioning to retain the builder arm in a depressed position and in an inoperative relationship relatively to a main builder cam of the machine which is carried by and rotatable with said driven cam shaft, said spring means including a spring stop mounted for longitudinal sliding movement on the buncher guide shaft adjacent the end thereof disposed remote to the supporting bracket, a setscrew carried by the spring stop and engaging the buncher guide shaft to adjustably secure the spring stop to said shaft for varying the tension of the spring means on the buncher guide member.
2. A bunch building attachment as in claim 1, said buncher guide member including a chamber disposed around a portion of the buncher guide shaft, a weight defining a segment of a ring loosely disposed in said chamber and movable therein in an arcuate path around the buncher guide shaft, said buncher guide member including a cylindrical wall portion surrounding said chamber and provided with a circumferentially extending slot, and a headed clamp screw having a threaded shank extending loosely inwardly through said slot and threadedly engaging said weight, said clamping screw permitting the weight to be circumferentially adjusted relatively to the buncher guide member when loose and being tightened for adjustably clamping the weight to the buncher guide member, said weight functioning to cause the ends of the thread of the buncher guide member to assume the same circumferential positions each time that the buncher guide member is returned by the spring means into a position beneath the buncher disk.

WILLIAM H. BUCKNER.
